STEREOSCOPIC APPARATUS IN RELATION
TO CINEMATOGRAPH REPRODUCTION
AND TELEVISION

Alan Philip Franklin, Lower Kingswood, England

Application August 25, 1944, Serial No. 551,128
In Great Britain August 31, 1943

5 Claims. (Cl. 88—29)

1

This invention relates to stereoscopic apparatus for viewing stereoscopic pictures and in particular to moving pictures resulting from cinematograph or television reproduction where a number of people have to view the same pictorial reproduction.

One of the difficulties experienced with the design and construction of any apparatus suitable for use by the public is that the average member of an audience will not use any device as an aid to vision which has to be held or manipulated continuously during a performance or which must be held close up to the eyes.

Another difficulty is that in stereoscopic reproduction any movement of the viewer which moves the eye-pieces of the viewing device out of the plane passing through the centres of the two pictures destroys fusion and the stereoscopic effect is at once lost. If the device is held or worn by the viewer the necessary restraint would be most irksome, whereas when the device is mounted in the manner described hereinafter in relation to my own invention this difficulty is overcome.

In the application of polarised light it has been suggested to provide special spectacles for viewing, but the drawback to the provision of glasses or other unattached device is that, apart from the expense, they are liable to become damaged or lost. If, however, they are made a fixture and adapted to my invention as hereinafter disclosed, this and other difficulties would be met.

The stereoscopic effect depends on the visual fusion of two pictures. A very few people can, with practice, train their vision to effect the fusion without any aid, but these are the exceptions and even they see a parasitic image on each side of the fused image, moreover, the concentration required imposes a definite strain. The majority of persons, therefore, must have some aid to vision in order that in spite of their natural but somewhat inflexible control of focus and convergence they can produce correct fusion of the two images without strain.

By use of a very complicated system of multiple lenses and concave mirrors, individual aids to vision might possibly be dispensed with, but at a prohibitive cost.

Persons using my apparatus in the home, could move their viewing pieces, and fixtures erected on a suitably weighted stand to any position to suit the angle of the prism. Prisms could be changeable but would be chosen for a normal distance from the television set so that 3 or more people can view it at the same time.

As the device is fixedly supported in position in 55 flaps 60.

2

front of the viewer the two eye pieces will always be maintained with their axes in a plane passing through the centres of the two pictures.

The device may be made of metal, cardboard or one of the well-known plastics or any other suitable material. The device can be moved to conform to any movement of the viewer.

In the simplest form no lenses or mirrors are needed for this invention. The probability is that only one prism will be necessary.

The device could also be used in the case of polarised light where the pictures to be viewed are superimposed. For this purpose a polarising filter would be fitted to each eye piece and the prism or prisms moved out of the line of vision.

The drawings which will now be referred to show the stages of development of the invention.

50 Figs. 17 and 18 are front and side elevations respectively of the device shown in Fig. 16.

Fig. 19 is a sectional plan view.

Fig. 20 is a transverse vertical section through one of the prism holders, and

Fig. 21 is an elevation of one of the butterfly

Referring to Fig. 1 which shows one form of apparatus made according to the invention comprising a vertical bar 1 carried on a support 2 which in turn is carried on a telescopic column 3 adjustable as to height, pivoted at 4 to a slide 5 mounted on a rail 6 secure to the backs of two seats in the row in front of the viewer. A handle 7 is provided to assist manipulation, and the device is maintained in position by tightening all pivots or other adjustable parts. A pair of eye pieces fitted with prisms 9 are arranged in relation to the bar 1 and are encased in a manner similar to the eye pieces of a stereoscope.

The bar 1 is made of such dimensions that if adjusted to its normal position it will block out 15 the view of the right-hand picture from the left eye and vice-versa so that the right eye of the viewer will only see the right-hand picture and the left eye the left-hand picture.

The operation of the device will be obvious from 20 the drawings, therefore no further description will be given.

The arrangement will avoid discomfort of any attachment which has to be worn and, as will be seen, the eye pieces are of such a size as to enable them to be positioned at from three to six 25 inches from the eyes of the viewer whilst permitting a full and correct view of the respective pictures to be obtained.

Referring to the construction shown in Figs. 30 2 to 6, the device comprises an outer casing *a* similar in shape to the eye mask of a stereoscope. Pivots *b* provided with wing nuts *c* are secured to and extend laterally from the casing to engage supporting arms *d*. Mounted within the outer casing *a* are inner casings *e* and *e'* which are provided with pivots *f* slidable in slots *g* in the outer casing and secured by thumb nuts *h*. The inner casings *e* and *e'* carry detachable flared tubes *j* and *j'* which are secured against unauthorized removal by light chains shown in Fig. 6 (25). Within the outer casing *a* is mounted an apertured partition *k* adjacent the ends of the tubes *j* and *j'*. The tube *e* is provided with a prism *m* whilst the tube *e'* may be open-ended or provided with a piece of plane optical glass to keep out draughts. The end of the tubes *j* and *j'* are closed by a cap *n* having an eccentric aperture shown in detail in Fig. 4.

Referring to the construction shown in Figs. 7 to 10 inclusive, this form of the device comprises a box-like outer casing 1 of substantially rectangular cross-section two ends of the box being left open. One end is shaped to form an eye mask 2. Portions 3 of the side walls adjacent the other end are removed and replaced by shutters 4 hinged at 5 the said shutters having upper and lower flanges which fit into the casing 1 and by friction therewith hold the shutters in the desired position after being set. The casing 1 is provided with a longitudinal partition 6 extending for part of the distance and two shutters 7 pivoted at 8 which may be brought together to form an extension or partition 6 or moved to the dotted line. At the mask end the box-like casing is provided with an apertured partition 9 which is inclined backwardly as in Fig. 10. In front of the partition 9 adjacent the right-hand aperture thereof is a detachable prism holder 10 provided with prism 11 the holder being slidable laterally and pivoted in the same manner as in the form shown in Figs. 2 to 6. A similar holder may be provided in front of the other aperture and carry plane glass to exclude draught.

The most convenient position for mounting the

device in the case of a cinema would be from the back of the front seat and slightly to one side to avoid the head of the front seat holder. They can be on either his left or right or alternated 5 according to circumstances, or the mounting can be accommodated in the recess between two seats and drawn out to the required position.

The mounting as shown in Figs. 5, 6 and 8 mainly comprises a standard 20 pivoted to a slide 22, the slide being capable of adjustment in a lateral direction, and the standard adjustable in a vertical direction. The slide 22 enables the apparatus to be moved to conform to any lateral movement of the viewer. The apertures in the eye-pieces as seen in Fig. 8 are elongated to allow for his movement up and down. After the device has been correctly positioned the various adjustable parts may be locked by a wing nut or a clamping device. The fitting arrangement of the tubes as shown in Fig. 6, comprises a fork 23 which receives the transverse pivot 24.

In order to avoid loss of parts all parts are made so that nothing can be detached, although they can be loosened for purpose of adjustment. The arrangement as shown in Fig. 6 enables the apparatus to be pushed away from the viewer to a position shown in full lines in which other members of the audience can readily pass up and down the row whilst the position shown in dotted lines illustrates the device adjusted for viewing.

If the tubes are made detachable and interchangeable each will be secured by a chain 25 or other link in order to avoid loss.

In order to reduce the aperture of the tubes in Figs. 2 to 6 to the desired size a detachable and interchangeable cap (Fig. 4) may be provided for each tube. In Fig. 7, however, adjustable shutters 4 and 7 are provided to serve the same purpose. Of course, for each seat a different aperture can be fixedly provided. This would obviate any adjustable apparatus.

In order to reduce the cost one prism only need be used and this can be located in one of the tubes, the other being left clear, preferably the 45 right. The angle of the prism would naturally be selected according to the position of the seat from which the pictures are to be viewed, but it has been found in practice that a prism of about 20° will give perfect fusion in the greater part of the auditorium so that special prisms would only be required for a small number of seats.

Minor adjustments may be effected by moving the apparatus nearer or further from the eye, the major adjustment being obtained by the prism.

55 In most cases the more important adjustments can be effected permanently for each seat, leaving only a few minor adjustments to be carried out by the members of the audience, which will only be of the simplest kind.

60 No new equipment will be required for projection as the complementary pictures are arranged side by side on the film and projected through the same lens.

In order to make use of the same size frame as 65 is now used in practice this area may be divided longitudinally of the film. This would normally make the pictures taller than they are wide. If this is objected to then by any known optical system the image can be turned through an angle of 90° in taking the pictures and reversed on projection. Each picture being half normal size the use at first would probably have to be restricted to small cinemas or news reel theatres but when it has been proved a success and the public have 70 become accustomed to the novelty the expense of

necessary modifications for application to larger buildings would be justified. In practice, it has been found by test that the smaller-sized pictures give ample view even in the back seats of a large cinema.

If this method of projection is adopted, it will mean that, with the same degree of magnification as for ordinary films the length of the two pictures together will be 30' and the height 10'. That means that the fused picture will be 15' x 10'. On the other hand, if the two pictures are taken square on the normal film, they could be projected without the 90° prism, to make a fused picture of 10' x 10'. If the cinemas will not enlarge their screens, so as to make them 30' long, the latter arrangement can easily be carried out.

Furthermore, if the square films, which I contend, and, as I have proved by tests, with third dimensional vision would be quite appropriate, are objected to, the picture would have to be one quarter the size of the normal picture assuming also that 20' is the maximum breadth available for the two pictures.

Referring to the form shown in Figs. 11 to 13, the device comprises a hollow body part or casting 1 having a mask portion 2 cut away to the approximate shape of the forehead and, therefore, somewhat similar in shape to the mask of the well-known stereoscope. The device according to the present invention however, differs essentially from a stereoscope in that the viewer should not press his forehead against the device or vice versa and should on the contrary always arrange the device so that it is clear of his forehead by a few inches. The mask portion 2 therefore only acts as a shield or shade to shut out unwanted light or views and so aid concentration.

Slidably mounted in the body 1 adjacent the mask 2 are two shutters or movable blocking pieces 3, carried in guides 4, the shutters 3 extending through slots 5 in the body 1, so as to be manually operable from outside the body 1. Each slideable shutter 3 is formed from a sheet of opaque material of rectangular shape to slide in the guides 4 and is provided with a rectangular aperture two inches square, the inner edge of which is spaced one inch from the edge of the shutter. The two slideable shutters are arranged to be able to overlap at their inner ends so that the opaque end portions of one inch width may overlap one another.

Arranged longitudinally down the centre of the body 1 and extending forwardly from adjacent the guides 4 is a central partition 6 of opaque material. Fixed to the central partition 6 adjacent the guides 4 is an opaque transverse fixed blocking piece 7 which is also of opaque material and one inch wide being bisected by the central partition 6.

Also mounted in the body 1 between guides 8 are prism mounts 9 holding the plane two inch prisms 10, the prism mounts 9 being provided with an extension 11 which extending for the full depth of the prism and being made of opaque material serves the dual purpose of a handle and a light excluder. The side walls of the body 1 are apertured at 12 to the full width of the prism mount 9 to enable the mount 9 to be withdrawn for the purpose of changing or cleaning the prism 10. Stops 13 which may be soldered or otherwise locked to the body 1 are provided to limit the outward movement of the prism mounts 9 and prevent unauthorized withdrawal.

Forward of the guides 8 the sides of the body 1 are inclined outwardly and terminate in pivoted shutters 14 of opaque material having actuating members 15 secured thereto which extend through arcuate slots 16 in the bottom wall of the body 1 a friction device or other means (not shown) being provided to hold the pivoted shutters 14 in position after being set. In a similar manner the central partition 6 terminates in two pivoted shutters 17 with actuating members 18 extending through arcuate slots 19. Secured to the bottom wall of the body 1 near the point of balance is a bifurcated lug 20, the wings of which are drilled at 21, to receive a rivet or bolt 22 shown dotted in Fig. 13.

In the drawings the prisms 10 are of relatively large angle and it is to be understood that such wide angle prisms would only be required for seats relatively close to the screen and that in many cases a single prism is sufficient the other being omitted or replaced by a piece of optical plane glass. The use of a single prism will reduce cost of manufacture.

Turning now to Figs. 14 and 15 of the drawings which show one form of adjustable mounting which enables the device to be moved to the desired position whilst guarding against its being tilted sideways.

Mounted on the back of the seat 30 is a bracket 31 pivotally supporting a vertical member 32 carrying a linked frame the members 33 to 38 of which form two coupled parallelograms the outer vertical member 38 carrying a vertical socket 39 in which is pivotally supported a pin 40 formed with a lug adapted to enter between the wings of the bifurcated lug 20 and drilled to receive the rivet or bolt 22.

Figs. 14 and 15 show clearly the movements which may be imparted to the device and its support. It will be obvious from Fig. 14 how the device can be raised or lowered, drawn towards the viewer or pushed away while Fig. 15 shows by dotted lines how the whole support may be swung sideways to conform to the regulations of the London County Council or other local authority, by pivoting about the member 32 or directed angularly by turning the device about the pivot 39. Fig. 14 also shows how the device may be tilted about the rivet or bolt 22. It should be noted that this arrangement entirely prevents any sideways tilting.

The device above described is best suited for use where the viewer gets a relatively clear space between two members of the audience sitting in the seats immediately in front. In some cinemas the seats are not so well arranged. In such cases the seats should be re-arranged or the screen raised. If this is not possible then the alternative but more elaborate modified construction shown in Figs. 16, 17 and 18 may be employed. In these figures the same reference numerals have been used to denote the same parts. Instead of direct vision, pairs of mirrors 51 and 52 are provided to enable the viewer to see past the head of the person in front. The body 1 is of modified shape to accommodate the mirrors and more closely resembles a pair of prismatic field glasses or binoculars. The mirrors 51 and 52 are set in adjustable mountings so that their angularity may be adjusted about pivots 53 to suit the seat from which the screen is to be viewed. Only very small angular adjustment would ever be required and the arrangement such that members of the public would not be able to alter the angularity once it had been set for the required

distance. In other respects the device is identical with that shown in Figs. 11 to 13 except that a single prism 10 is shown on the right-hand side and a piece of plane optical glass 53 on the left side. Two prisms may, of course, be used and in this construction as the mirrors can be adjusted to produce fusion the use of a prism could be dispensed with. However, the adjustment of the mirrors being very delicate, a more rapid and accurate fine adjustment can be secured empirically by changing the prism for one of a different angle.

Turning now to Figs. 19 and 20 which show the latest and most simplified form of the device which was evolved from that illustrated in Figs. 11 to 13 of the drawings. Wherever possible the same reference numerals have been used to indicate the same parts as in Figs. 11 to 13, and only the differences will be noted.

The following differences will be noted:

1. The central front flaps 17 have been dispensed with.
2. The shutters 14 have been lengthened and the pivots made a good firm fit so that the pins 15 and slots 16 are no longer necessary.
3. Instead of the sliding shutters 3 a pair of hinged butterfly shutters 60 are mounted on the partition 6 within the mask 2, the hinges being made stiff so that the butterfly shutters 60 remain in the position in which they are set.
4. The blocking piece 7 has been omitted.
5. The prisms 10 are nearer the eyes.
6. The top and bottom of the mask 2 are not cut away and so cover the butterfly shutters 60.
7. Stops 13 to prevent removal of the prism holders are formed on the inner end of the prism holders instead of on the casing as shown in Figs. 1 to 6.
8. The prism mounts have been modified to ensure a smooth sliding action and a steady mount, as will be seen from Fig. 20 of the drawings filed herewith.

9. The sides of the device have become straightened to reduce the number of corners and simplify construction. It may be found that without the blocking piece when the prism or glass holders 9 are drawn out slightly for adjustment light is admitted in the centre. It is probable that the butterfly shutters 60 when opened out to the correct extent will exclude this unwanted light from the eyes. If not, it would be an easy matter to provide extensions at the inner ends of the prism holders 9 which will slide through slots in the central partition 6 and overlap each other when the prism holders are pushed in to the full extent. These extensions should not need to be more than $\frac{1}{2}$ " wide.

As will be seen from Fig. 21 the top and bottom corners of the free edge of the butterfly flap 60 have been rounded off. This avoids sharp corners and is found in practice to be the most suitable shape.

To enable the device to be used in the home in conjunction with television sets, the support may comprise a weighted pedestal which can be stood on the ground in the desired position.

For use in a cinema the device will be equipped with all adjustments set according to the distance from the seat to the screen and the angle subtended by the two pictures so that for normal vision perfect fusion would be obtained. Whichever form of device is installed the viewer after taking his seat and making himself comfortable will draw the device down and towards him until it is only a few inches in front of his face and will

set it angularly to direct it onto the screen. He will then make such adjustments as may be necessary to ensure that with his left eye he can see only the left hand picture and with the right eye only the right hand picture. It will be found that quite an appreciable movement of the head may be made without much loss of vision. The shutters and prisms may be pre-set for normal use and will only require adjustment so that the pictures fuse in the most comfortable position. It may also be necessary to make a slight adjustment of the prism or prisms 10 by sliding them in or out in order to look through the centre of the prism as some people are much wider between the eyes than others. Once set, however, no further adjustment is necessary. If anyone wishes to pass or if the viewer wishes to leave or, in the case of an emergency, the device can be swung instantly out of the way.

- 20 10 The fixture will be such that if the viewer wishes to lean over to one side or alter his position in any way, he can bring the device with him, by the very slightest movement of the instrument or the fixture. He will in most cases be able to continue to view the pictures without any further adjustment, having drawn the device to the most comfortable position in front of the eye as before. With some kind of "angle-poise" fixture this is an easy matter.
- 25 30 A further advantage is that as the device is supported at a reasonable distance from the eyes the viewer if obliged to wear spectacles may do so without inconvenience.

For the sake of convenience and when time permits the device when out of use should be pushed straight away from the viewer so that it is behind or between the heads of the persons in the row in front, in the best position for the comfort of others.

- 40 35 40 A device made according to the present invention can be used for several purposes.

(a) It can be employed with private television sets being suitably mounted in a fixed relation.

- 45 45 (b) It may be used in a cinema for viewing stereoscopic pictures projected on the screen for a film projector.

(c) With suitable modifications and adjustments it can be adapted for use with complementary pictures arranged side by side in the normal manner of viewing stereoscopic pictures or it can be used for viewing superimposed pictures, separation of the two pictures being obtained by the bi-colour known process (which cannot at present be used for viewing stereoscopic pictures in colour), or the use of polarised light, the device being provided with red and green glasses or polarised filters in the already well-known manner for effecting separation of such pictures in place of the prisms. The prisms or plain glass eye-pieces could be removed and the necessary eye-pieces inserted.

- 50 55 60 65 70 75 If a member of the audience does not wish to see stereoscopically but wishes to view one picture normally without any aid to vision, the prism or prisms would have to be drawn out of the line of vision, and the line of vision from the two eye-pieces confined to one picture which, in the latest device, is secured by closing the front shutters so that only one picture can be seen either through plain glass or direct. In the case of the earlier tubular construction this would be effected by pivoting both tubular extensions to direct them both onto the same picture. Some seats could be kept for this purpose, preferably the outside

seats of the stalls, where practice has shown that the stereoscopic effect is not quite as arresting.

It is intended that in the design finally adopted for production every reasonable measure will be adopted to render the device foolproof and to guard against loss or damage or the removal by unauthorised persons of the device or any of the parts thereof.

For the purpose of photographing the pictures to be viewed an ordinary cinematographic camera can be used, and one way of converting it to take stereoscopic pictures is to fix a simple attachment to the lens of the camera. This attachment will consist of a box-like member the apertures of which (at each end) will be the size of the film to be taken but there will be a partition down the centre. From each side of this partition two tubular members diverge to eye distance apart. In the ends of these tubes prisms are placed and two parallel extensions connected to the tubes are positioned to face the direction of the camera's view finder; thus the light passing through each eye-piece is bent by the prisms down the tubes and directed through each side of the box-like attachments to the camera lens. The parallel extensions can be made conical to take the whole picture or probably a better arrangement would be to have the two lenses one at the end of each extension instead of a single lens as heretofore described or of a split lens. The lens of the camera can be detached and replaced by the box-like structure above described. The angle between the end tubes and the divergent tubes can be as large as possible and the degree of refraction of the prisms correspondingly small.

The prisms can be made of glass, plastics or other material such as perspex and this can equally apply to the prisms in the viewing or projecting device. This method of converting the cinematograph camera into an apparatus capable of taking stereoscopic pictures will be both simple and inexpensive.

Some or all of the following advantages are claimed for the various forms described:

1. It is the only form of stereoscope known for viewing pictures at a distance or more than about a foot.

2. No focussing is required when used in a cinema because the prism used is not a lens. When a lens is used this is one which does not require focussing.

3. The prism angle is selected according to distance and size of picture to be viewed.

4. Only one prism is required in most cases.

5. The only stereoscope in which blocking pieces and apertures are adjustable. Such adjustments may be fixed for each seat and there need be no further adjustment.

6. The device is a fixture requiring no holding or wearing and need not be positioned close to the eyes, but viewed at any distance up to that of about 6" from the prism. The fixture arrangement is novel for a cinema as well as in the home for a television set.

7. As it is a fixture the stereoscopic effect is not lost by movement as with spectacles or other devices fixed to the head.

8. Large eye-pieces give greatest possible scope for head movement of viewer and provide great comfort in viewing and enable the viewer to choose his own distance, whereas the usual stereoscope has small eye-pieces and must be viewed close up.

9. Anyone who has to wear spectacles can do so

without affecting the correct functioning of the device.

Apart from the novelty of the fixture in front of the viewer to keep the prism level and to provide the minimum discomfort and inconvenience to the audience (thus overcoming the usual objection to visual aid), there is novelty and ingenuity in the inference subsequently confirmed by a test in a cinema that perfect stereoscopic effect can be produced without magnification in the viewing apparatus, the necessary magnification being fully provided by the projector. The prism used is therefore plain glass and no focusing is required. It has been possible thus to overcome the difficulty that has so often presented itself in dealing with this problem, namely, how to combine focus and fusion in a stereoscope made for viewing at a distance. It has always been laid down that for perfect stereoscopy fusion and magnification must both be included in the viewing apparatus. A prism which did not embody a magnifying lens was therefore abandoned as useless many years ago in making the original stereoscopes.

25. What I claim and desire to secure by Letters Patent is:

1. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

45. 2. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

50. 3. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

55. 4. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

60. 5. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

65. 6. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

70. 7. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

75. 8. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings.

11

an adjustable fixture supporting said device, a socket member adapted to be secured to a fixed support, a vertical member pivotally mounted therein, a jointed frame pivoted thereto for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings, prisms for said viewing device, means enabling said prisms to be interchanged whereby the apparatus is usable from any part of an auditorium of a cinema.

4. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto, for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative

thereto about an axis parallel to a line joining the centres of said sight openings, a lens for said viewing device, said lens being not more than one-half diopter and mounted in the line of vision of one eye.

5. Stereoscopic apparatus for viewing adjacent pictures at a distance, comprising, a viewing device having two sight openings and means for effecting fusion in the eyes of the viewer, of the images seen by his two eyes therethrough, and an adjustable fixture supporting said device, a socket member adapted to be secured to a fixed support, a vertical member pivotally mounted therein, a jointed frame pivoted thereto for partial rotation in a vertical plane and having an horizontal joint permitting adjustment of the outer part of said frame in said plane towards and away from said socket member, a vertical pin rotatably mounted in the outer part of said frame, and means for pivotally mounting said device upon said pin for angular adjustment relative thereto about an axis parallel to a line joining the centres of said sight openings, said adjacent pictures being of half normal width positioned side by side and said viewing device providing magnification whereby no alteration in the projecting apparatus, or enlargement of the screen is required and only half the area of the normal size of each individual frame, and half the area of the screen being used, provided the usual proportion of length to breadth of the individual picture is retained.

ALAN PHILIP FRANKLIN.
